UNITED STATES PATENT OFFICE.

CARL T. BLOOM, OF OAKLAND, CALIFORNIA, ASSIGNOR OF ONE-HALF TO LEE TUNG,
OF OAKLAND, CALIFORNIA.

DESIGN FOR AN AUTOMOBILE SIGNAL CASING.

Application filed April 4, 1925. Serial No. 13,021. Term of patent 14 years.

To all whom it may concern:

Be it known that I, CARL T. BLOOM, a citizen of the United States, residing at Oakland, in the county of Alameda and State of California, have invented a new, original, and ornamental Design for Automobile Signal Casings, of which the following is a specification, reference being had to the accompanying drawing, forming part thereof.

Figure 1 is a top view of an automobile signal casing showing my new design. Fig. 2 is a face view from either side of the same, and Fig. 3 an end elevation from either end, the relatively long element at each end being glass.

I claim:

The ornamental design for an automobile signal casing, as shown.

CARL T. BLOOM.
